UNITED STATES PATENT OFFICE.

GEORGE L. KEMPER, OF CHICAGO, ILLINOIS, ASSIGNOR OF ONE-HALF
TO CHRISTOPHER A. ROFF, OF CHICAGO, ILLINOIS.

STAMP OR LABEL AFFIXING DEVICE.

SPECIFICATION forming part of Letters Patent No. 772,660, dated October 18, 1904.

Application filed March 19, 1903. Serial No. 148,547. (No model.)

To all whom it may concern:

Be it known that I, GEORGE L. KEMPER, a citizen of the United States, and a resident of the city of Chicago, in the county of Cook and State of Illinois, have invented certain new and useful Improvements in Stamp or Label Affixing Devices; and I do hereby declare that the following is a full, clear, and exact description of the same, reference being had to the accompanying drawings, and to the letters of reference marked thereon, which form a part of this specification.

This invention relates more particularly to a device for automatically attaching postage-stamps on envelopes and labels on bottles, packages, or the like, said stamps or labels being arranged in strips and wound upon a roll or spool, from which they are fed to the machine.

The object of the invention is to provide a small, compact, and comparatively inexpensive device which acts to automatically moisten the surface upon which the stamps or labels are to be affixed, detach the stamps or labels singly from the strips, and press the under side thereof upon the moistened surface.

The invention consists in the matters hereinafter described, and more fully pointed out and defined in the appended claims.

In the drawings, Figure 1 is a front elevation of a device embodying my invention with the front wall-plate removed. Fig. 2 is a section taken on line 2 2 of Fig. 1. Fig. 3 is a section taken on line 3 3 of Fig. 2. Fig. 4 is a section taken on line 4 4 of Fig. 3. Fig. 5 is a section taken on line 5 5 of Fig. 3. Fig. 6 is a similar view showing the parts in position to sever and affix the stamp. Fig. 7 is a detail view of the moistener-operating mechanism. Fig. 8 is a bottom plan view of the stamp feed and severing means.

In said drawings, A indicates as a whole a casing having side walls a' , front a^2 , back a^3 , and top a^4 . Said top is provided near the center thereof with a transverse aperture, the central portion of which is closed by a plate a^5 , rigidly but removably secured to the top.

Within the casing A is secured a plunger, having at its lower end a rectangular casing B smaller than and within the casing A and adapted to carry the stamps and having side walls b' , front b^2 , and back b^3 , corresponding with the walls of the casing A. The sides b and b' are provided, respectively, with arms b^4 and b^5 , which normally extend upwardly through the aperture in said top a^4 of the casing and on opposite sides of the plate a^5 a distance approximately equal to the travel of the plunger. Said arms are integrally connected at their upper ends, and a hollow handle b^6 is rigidly secured thereon, into which extends a vertical stem or shaft b^7 , rigidly secured on the plate a^5 . Within the handle is secured a spring b^8 , which presses against the top of the stem and acts normally to hold the plunger as a whole in its raised position. The side walls b' of said plunger are provided with outwardly-extending lugs b^9 b^9 , which slide in vertical ways a^6 a^6 , formed on side walls a' and a^4 , and serve to guide and steady the plunger in its movement.

A shaft C is journaled transversely in the walls of the plunger-casing and projects beyond the wall b . Near the center of said shaft and rotative therewith is a friction-wheel C', provided with a tire c, of rubber or other resilient and friction-producing material. A chute D, adapted to convey the stamps to the plunger, is rigidly engaged in the casing B to the side walls b' and extends upwardly through a slot in the casing and on its upper end is provided with rearwardly-extending bracket-arms d, in which is journaled a shaft d', carrying a roll or spool d², adapted to have wound thereon a strip of stamps or labels in position to feed down the chute. On one end of said shaft is a friction-wheel d³, rotative therewith and adapted to be engaged by a leaf-spring d⁴ or the like rigidly engaged on the adjacent bracket-arm and which acts to regulate the feed of the stamps to the plunger. The lower end of said chute is curved forwardly beneath the friction-wheel C' into close proximity therewith and is provided with a longitudinal slot through

which the wheel C' acts to frictionally engage the stamps and project them from the mouth of the chute. On the projecting end of the shaft C, adjacent to the wall b, is loosely journalled a pinion c', adapted to mesh with an upright rack-bar c², rigidly secured on the rear wall of the casing A. Adjacent to the pinion is a ratchet-wheel c³, rigidly secured upon the end of said shaft and engaged by a pawl c⁴, carried on said pinion. When the plunger is forced down, the pinion c' coacting with said rack-bar rotates upon the shaft, and when it is raised the detent engages the teeth of the ratchet-wheel c³ and causes the shaft and friction-wheel C' to rotate therewith, thereby imparting to said friction-wheel an intermittent motion, and the construction is such that with each rotation of the wheel it moves the strip downward the length of one stamp or label. The tension of the wheel C' upon the stamps is regulated by means of a set-screw c⁶, which is movably engaged in an apertured lug c⁵, integral with the rear wall of the plunger-casing, said screw extending forwardly into position to engage the lower end of the chute and regulate the distance between it and said wheel.

A strike-plate E, which coacts with the end of the chute to sever the stamps from the strip, each having serrate cutting edges, is pivotally engaged, with its outer face flush with the lower margin of the walls b b'. A longitudinally-apertured block e is rigidly engaged on the inner side of the wall b and contains a push-pin e', the upper end of which is engaged by a coiled spring e², (shown in dotted lines in Figs. 5 and 6,) and the lower end engages the front side of the strike-plate and acts normally to incline said plate sufficiently to permit the stamp or label to pass down out of the chute and beneath the same.

The moistener consists of a swinging plate F, provided on its under side with a pad of absorbent material and slidingly pivoted on the side walls of the casing A by means of curved cam-levers G, having cam-slots f f' therein, in which are slidably engaged pins f' f', rigidly engaged on the flanges f² f², integral with said plate. Said pins also extend beyond said flanges and engage in guide-slots in the side walls a a' and direct the movement of the plunger. Pins b⁴ extend through cam-slots f³ in the flanges f² and engage in the side in position to permit the plate to swing forwardly and upwardly thereon into position parallel with the front wall a² of the casing A. The cam-levers G are centrally pivoted upon pins g g, rigidly secured on the walls a a', adjacent to and in front of the lower ends of the ways a⁶. Said levers at their rear ends are bent obliquely with their axis and provided with longitudinal slots g² g², which slidingly engage pins g³ g³, rigidly fixed in the lower margins of the side walls

b b' of the plunger-casing. A receptacle H is provided on the front of the casing A and opening therewith adapted to contain absorbent material H', against which the absorbent material of the moistening-plate presses when the plunger is lowered, thereby wetting the same.

The operation of my device is as follows: A roll of stamps or labels is secured on the chute and the end entered within the chute, extending to the bottom thereof. When the plunger is in its normal or raised position, the moistening-plate is in contact with the surface upon which the stamp is to be placed and wets the same sufficiently to allow the stamp to be affixed thereto. When the plunger is forced downward, the rear ends of the cam-lever G are also forced down by means of the pins g³ g³ acting in the slots g² g², and the front ends of said levers are forced upwardly, carrying the moistening-plate, which is given a quarter-turn through the action of the slots f f' and f³ f³ acting on their respective pivots. When the plunger approaches its downward limit, the front end of the strike-plate engages the surface upon which the stamp is to be placed, and swinging upon its pivots the teeth on its rear margin coact with those on the lower end of the chute, severs the lower stamp from the adjoining ones and firmly presses it upon the surface. When the plunger is raised, the feeding mechanism forces another stamp into position to be severed, and the moistening-plate returns to its normal position.

Obviously many details of construction may be varied without departing from the principles of this invention.

I claim as my invention—

1. In a stamp-affixing machine, in combination a casing, a stamp-receptacle and feeding means therewith, a plunger, and a pivoted vertically-adjustable strike-plate carried by the plunger having a cutting edge adjacent the mouth of the stamp-receptacle.

2. In a stamp-affixing machine, in combination, a casing, a vertically-reciprocating plunger and cutter therein, a stamp-receptacle carried by the plunger having a mouth across which the cutter works to sever a stamp projected therefrom, a feed-roller to project stamps from the receptacle beneath the plunger, and means to operate the roller.

3. In a stamp-affixing machine, in combination a vertically-reciprocating plunger in a casing, a stamp-receptacle carried by the plunger, a pivoted strike-plate at the bottom of the plunger having a cutting edge crossing the mouth of the receptacle when the plunger is depressed, and means to project stamps from the receptacle beneath the strike-plate.

4. In a stamp-affixing machine, in combination, a casing, a vertically-reciprocating plunger therein, a stamp-receptacle carried by the

plunger, means to feed the stamps therefrom, a swinging moistener and means to swing the same, and a pivoted strike-plate at the lower end of the plunger having a cutter adjacent to the mouth of the receptacle actuated by contact of the strike-plate with the envelop to pass across the said mouth and sever a stamp projected therefrom.

5. In a stamp-affixing machine, in combination, a casing, a vertically-reciprocating plunger therein, a stamp-receptacle reciprocating therewith, a shaft adjacent the mouth of the receptacle, a feed-roller thereon, rack-and-pinion mechanism to actuate the shaft, and a pivoted strike-plate carried by the plunger to sever a stamp.

6. The combination with a casing, of stamp-carrying means therein, reciprocating feed mechanism for the stamps, oscillating moistening means and a pivotally-supported plate beneath which the stamps are fed acting automatically to sever the same and press the same into position.

7. The combination with reciprocating stamp-carrying and actuating means, of a moistener actuated thereby and a pivoted plate having a serrated edge acting with a like edge on the stamp-carrying means and acting to sever and to affix the stamp.

8. In a stamp-affixing device the combination with an outer casing, of a plunger therein, a stamp-feeding chute movable therewith, an intermittent friction-wheel adapted to engage and project the stamps through the chute, means dependent on the operation of the plunger and acting to operate said wheel, means for regulating the distance between said chute and said wheel and automatic means for detaching the stamps from the strip.

9. In a stamp-affixing machine the combination with a casing, of a plunger in said casing, means acting to guide the plunger therein, an intermittently-revoluble friction-wheel journaled within said plunger and operated by the movement thereof, a longitudinally-slotted stamp-chute rigidly engaged within the plunger and having its lower end curved forwardly beneath the friction-wheel, means for regulating the distance between the chute and the wheel, means for severing the stamp from the strip, and moistening means also operated by the plunger.

10. In a device of the class described the combination with an apertured casing, of a plurality of parallel ways within said casing, a reciprocating hollow plunger, outwardly-extending lugs thereon slidingly engaged in said ways, a longitudinally-slotted chute carried on said plunger and extending through the top of the casing, a plurality of bracket-arms thereon, a shaft journaled in said arms, a spool revoluble therewith, a friction-brake on the outer end of said shaft, a transverse

shaft journaled in said plunger, means adapted to intermittently rotate said shaft, a friction-wheel rigidly engaged on said shaft, resilient means on the periphery of said wheel adapted to engage the stamps and eject them from the lower end of said chute, a set-screw movably engaged in the plunger-casing adapted to engage and adjust the chute and a strike-plate adapted to detach stamps from the strip and affix them upon an envelop or the like.

11. In a device of the class described the combination with an outer casing having parallel ways therein, of a plunger-casing reciprocating in said ways, upwardly-extending arms thereon, a stem, a hollow handle on said arms adapted to reciprocate on said stem, a spring adapted to engage said stem and normally hold the plunger in its raised position, a serrated stamp-chute carried on the plunger, a shaft journaled transversely in the plunger-casing and extending through one side thereof, a resilient friction-wheel adapted to engage the stamps and eject them from the lower end of said chute, a pinion journaled on said shaft, a spring-operated pawl carried thereon, a rack-bar adapted to engage said pinion, a ratchet-wheel rigidly rotative with the shaft adapted to be engaged by the detent during the upward movement of the plunger, and a serrated strike-plate pivotally engaged on the plunger-casing adapted to contact with the lower end of the chute when the plunger is lowered.

12. In combination, an outer casing, parallel ways therein, a plunger-casing reciprocating in said ways, a chute leading therein, means for projecting stamps or the like through said chute, means for adjusting the chute in respect to the stamp-projecting means, a strike-plate pivoted in the lower part of the plunger-casing having its lower edge normally extended below said casing in position to engage the surface upon which a stamp is to be placed and detach the stamp from the stamp-strip and press it upon said surface, a longitudinally-apertured block rigidly engaged in said casing, a spring-operated push-pin therein adapted to engage said plate and return it to its normal position, a swinging moistening-plate and a receptacle integral with the outer casing adapted to supply moisture to the moistening-plate.

13. In a stamp-affixing machine, an outer casing, a reciprocating plunger therein, a stamp-chute rigidly engaged in said plunger, means for projecting the stamps therethrough, means for adjusting the chute in respect to the stamp-projection means, means for detaching the stamps and placing them upon envelops or the like, a moistening-plate, lateral flanges thereon pivoted in the outer casing, a slotted cam-lever pivoted centrally thereof on the outer casing having its forward

end slidingly pivoted on said flanges and its rear end slidingly pivoted on the plunger, a receptacle on the front of the casing opening thereinto, and absorbent material therein 5 against which the moistening-plate engages when the plunger is lowered.

In testimony whereof I have hereunto sub-

scribed my name in the presence of two subscribing witnesses.

GEORGE L. KEMPER.
